UNITED STATES PATENT OFFICE.

OLE L. FURUSETH, OF BELMOND, IOWA.

FRUIT-DRIER.

1,093,044.

Specification of Letters Patent.

Patented Apr. 14, 1914.

Application filed December 8, 1913. Serial No. 805,438.

To all whom it may concern:

Be it known that I, OLE L. FURUSETH, a citizen of the United States, residing at Belmond, in the county of Wright and State 5 of Iowa, have invented certain new and useful Improvements in Fruit-Driers, of which the following is a specification.

This invention relates to improvements in fruit driers and its object is to produce a 10 device of this class comprising a plurality of drawers or cases retained in a rotary frame which is supported by suitable standards. By means of said rotary frame the cases may be inclined at any angle with the 15 horizontal desired in order to permit the fruit therein to receive the rays of the sun from any position of the latter in the firmament. Said drawers are also so secured to said circular frame as to be movable longitudinally independently of each other 20 whereby the top drawer may be used to obscure a lower drawer from the sun's rays when desired, as in the case of fruit that may be dried in the air away from the direct 25 heat of the sun.

With the foregoing and other objects in view the invention consists in the combination and arrangement of parts to be herein-after fully described in the following specification, pointed out in the claims and illustrated in the accompanying drawings which 30 form a part of said specification and in which—

Figure 1 is a front elevation of my improved fruit drier. Fig. 2 is a plan. Fig. 3 is a side elevation showing, in dotted lines, how the movable parts of a case may be extended. Fig. 4 is a section taken on line 4—4 of Fig. 2. Fig. 5 is a section taken on 40 line 5—5 of Fig. 2.

Like reference characters indicate corresponding parts throughout the several views.

My fruit drier comprises a base 1 carrying standards 2, 2 to which rotary circular frames 3, 3 are secured as at 4, 4. To receive the fruit I provide a plurality of cases 5, each of which contains a sliding drawer

6, provided with a sliding top screen 7 and a sliding bottom screen 8. Each drawer 6 50 may be extended with relation to the case 5 together with or independent of either of its screens 7, 8 and each drawer is further provided with a handle 9. Each case 5 is slidably secured to the rotary frame 3 by 55 means of a plurality of bolts 10 which extend through elongated slots 11 in said frame whereby each case is movable longitudinally independently of any other case to a limited extent. 60

To help shut out the sunlight from a lower case by means of a relatively upper one the upper one may be moved longitudinally in the direction from which the sun's rays are received and the extent of this movement 65 will depend upon the position of the several bolts 10 in the rotary frame and the length of the elongated slots 11.

To tilt the several cases the rotary frames 3, 3 are moved upon their pivots 4 and 70 locked in adjusted position by means of a pin 12 carried by one standard 2 for insertion in one of the apertures 13 formed in the frame 3 in a circle having the said pivot as its center. 75

What is claimed is:—

1. In a fruit drier, an adjustable rotary frame suitably supported, cases secured in said rotary frame provided with drawers and top and bottom screens carried by said 80 drawers and movable with or independently thereof.

2. In a fruit drier, an adjustable rotary frame suitably supported, cases secured in said frame slide longitudinally independently of each other, drawers in said cases and top and bottom screens carried by said 85 drawers and movable with or independently thereof.

In testimony that I claim the foregoing as 90 my own I have hereto affixed my signature in the presence of two subscribing witnesses.

OLE L. FURUSETH.

Witnesses:

G. D. MARTIN,
JOHN GREENLANDER.
